UNITED STATES PATENT OFFICE.

JAMES G. WALKER, OF MORO, OREGON.

ATTACHMENT FOR THRESHING-MACHINES.

SPECIFICATION forming part of Letters Patent No. 707,287, dated August 19, 1902.

Application filed September 21, 1901. Serial No. 76,068. (No model.)

To all whom it may concern:

Be it known that I, JAMES G. WALKER, a citizen of the United States, residing at Moro, in the county of Sherman and State of Oregon, 5 have invented a new and useful Attachment for Threshing-Machines, of which the following is a specification.

My invention is an improved attachment for threshing-machines, and relates particularly 10 to an arrangement for automatically feeding the straw to either the feeding elevator or cylinder of the threshing-machine.

In running a steam-thresher for threshing headed wheat it is often found necessary to 15 arrange a derrick-table upon which is positioned men for hoeing down the straw from where it is dumped by the derrick-fork onto the table to the elevator of the feeder; and it is the object of my attachment to provide a 20 device whereby the straw will be positively and automatically fed, and thus dispense with the services of the men for doing this work. In carrying out this object I provide a frame 25 to be attached to the thresher having a feed- belt that is geared to the machine for feeding the straw to the chute thereof and at the lower or discharge end of the belt to provide an automatic feeding device for pushing the straw into the cylinder-chamber or on the 30 feeder-elevator.

With these objects in view my invention also consists in the peculiar construction and novel combination and arrangement of parts, as will be fully described in the following specification and pointed out in the claim, reference 35 being had to the accompanying drawings, in which—

Figure 1 is a perspective view of my improvement detached from the threshing-machine. Fig. 2 is a plan view of the same with portion thereof removed. Fig. 3 is a longitudinal section of the frame attached to a portion of a threshing-machine; and Fig. 4 is a detail cross-section thereof, taken about on 45 the line 4 4 of Fig. 3.

In carrying out my invention I employ a frame A, which I shall term a "derrick-table" and which consists of the side portions A' A', having their upper ends provided with 50 lateral extensions or platforms A² A², upon which is suitably held the derrick-frame B, whose upper cross-bar b is designed to hold

a pulley B', through which a rope runs for operating a gripping-fork. (Not shown.) Journaled in the front and rear ends of the 55 frame and at opposite corners thereof are shafts C C, carrying sprocket-pulleys C' C', over which run belts C² C², carrying cross-slats C³ C³, that are provided with projecting spurs or fingers, and between the side members of the frame is securely held an inclined metallic platform or bed D, the ends thereof being curved to encircle the shafts to prevent the straw from catching and being wound thereon. The shaft in the forward end of the 60 frame is extended upon one side and provided with a sprocket-pulley E, over which runs a belt E', that works upon a pulley E², arranged upon a drive-shaft E³, which is supported by either the bed-pieces or beams E⁴, 65 extending from the frame, as shown. This shaft is also provided with a gear-wheel F, which meshes a similar wheel F', carried by a cranked shaft G, which is also supported by the said extensions E⁴, and upon the laterally-projecting portions A² of the frame is secured brackets a a, in which is journaled a second cranked shaft H, the said shafts each having a sprocket-wheel g and h, respectively, over which runs a belt I for transmitting motion to the said shaft H. The drive-shaft E³ has a belt-pulley e arranged 70 on its end opposite the gear-wheel F, over which runs a belt from a pulley carried by the threshing-machine and which imparts 75 movement to the shafts, as will be readily understood.

Suitably held to the crank portions G' and H' of the shafts G and H is a feeder J, consisting of the side members J' J', to which 80 are connected cross bars or slats K K, carrying teeth K', as shown. This frame is located directly above the feeding-chute of the threshing-machine, and as the straw is fed down the incline the feeder will force the straw down 85 through the mouth of the threshing-machine onto the feeding-cylinder or on the feeder-elevator, and it will be further understood that by connecting the feeder to the cranks of the shaft the latter will be given irregular 90 rotary movement as the shafts revolve, which pushes the straw down, as will be readily understood.

From the foregoing description it will be

readily seen that I provide a very simple and compact device whereby the feeding of the straw is automatically accomplished and the services and expense of the men for doing 5 the work thereby avoided.

Having thus fully described my invention, what I claim as new, and desire to secure by Letters Patent, is—

A device of the kind described, comprising 10 a frame consisting of an inclined bottom, vertical sides, lateral extensions or platforms arranged upon the upper edges thereof, a derrick mounted upon the said extension or platform, a feed - belt operating within the 15 frame, an extension provided at one end of the frame, a drive-shaft journaled in the end of the extension and having a pulley arranged upon one end, and a gear and sprocket wheel upon the other end, a cranked shaft journaled

in the extension and having a sprocket-wheel 20 at one end and a gear mounted upon the opposite end that meshes the gear of the drive-shaft and a cranked shaft mounted in the frame and having a sprocket-wheel thereon, that connects through a chain belt to the 25 sprocket of the cranked shaft in the said extension, bars connected to the cranked portions of the shafts and having toothed cross-bars connected thereto one of the shafts of the feed - belt having a sprocket that connects to the sprocket of the drive-shaft, substantially as shown and for the purpose specified.

JAMES G. WALKER.
